AUTOMOBILE BODY INSIDE PANEL
FASTENER

Edwin G. Krentler, Detroit, Mich.

Application May 31, 1932. Serial No. 614,460

3 Claims. (Cl. 45—133)

This invention relates to a method of and means for attaching panels or similar sheets or sections to a framing or other support, and more particularly to means for securing the inside covering or finish of motor vehicle bodies to the body frame or other part. An object of the invention is to greatly facilitate the applying of finishing panels or the like to the inside of motor vehicle bodies and in a manner whereby all fastening means is concealed by the panels and the panels are secured in place without the use of tools, said fasteners being quickly applied to a made up panel and then those fasteners engaged within openings in the body frame or other support to which the panel is to be applied. It is also an object to provide fasteners for the purpose which are very simple and cheap to manufacture and the construction of which is such as to provide for a limited adjustment of the panel in securing it in place. A further object is to provide certain other new and useful features, all as hereinafter set forth and more particularly pointed out, reference being had to the accompanying drawing in which;

Figure 1 is a perspective detail of a portion of the forward end of a motor vehicle body showing a door thereof in open position and a corner of a panel on the door, broken away to disclose the construction;

Fig. 2 is an inside elevation of the lower portion of a body door, showing a panel in place thereon;

Fig. 3 is an elevation of the back side of a panel detached and showing fasteners applied thereto;

Fig. 4 is an enlarged cross section of door and panels, substantially upon the line 4—4 of Fig. 2;

Fig. 5 is a perspective detail of a portion of a panel, showing in perspective a fastener applied thereto; and

Fig. 6 is a perspective view of a fastener detached.

As illustrated, the invention is shown as applied to securing the inside finishing panels of vehicle bodies to the body frame, but it will be understood that the invention may be applied to other uses wherever applicable. One such panel, indicated as a whole by the numeral 1, is shown for convenience as applied to the lower part of the frame 2 of a door of the car, said panel comprising the usual sheet of fiber board 3 which is cut to a size and shape to fit the place where it is to be secured upon the frame and this sheet is covered in the usual manner, by a sheet of fabric or cloth 4 with the edges 5 of this cloth turned inwardly over the edges of the board 3 and firmly attached thereto by connecting said edges 5 firmly

down upon the back face of the board, this fabric being spaced from the opposite or front face of the board throughout its entire area, by a suitable padding 6 interposed between said fabric and the adjacent front face of the board.

Each complete panel 1 is attached to the body frame 2 or other suitable support for the paneling, by forming, as shown in Figs. 1 and 4, said frame 2 with the desired number of holes 7 bored inwardly from the inner face of the frame, to which face the panel is to be secured.

Suitable fasteners, indicated as a whole by the numeral 8, are attached to the board 3 adjacent its edges, in the manner hereinafter described, and these fasteners are each formed with a spring 70 prong to be forced into one of the bores 7, and is so arranged that after being forced in, this prong will engage the wall of the bore and securely hold the fastener against being pulled out of this bore in the frame.

Each of these fasteners 8, comprises a hook or loop 9 having a comparatively long lip 10 adapted to be inserted in a hole 11 formed in the board 3 adjacent the inner edge of the turned over edge portion 5 of the fabric covering, there being as many of these holes 11 as the number of fasteners to be employed to hold the panel in place, and each of these holes 11 is preferably of considerably greater diameter, than the width of the flat spring metal strip forming the fastener, so that the lip 10 may be easily inserted in the opening 11, and will be freely adjustable therein, said lip 10 being of considerably greater length than the diameter of the opening, so that it cannot be readily detached therefrom by a movement of the panel

away from the face of the frame, and so that said lip will yieldingly engage the face of the board, the board and edge 5 of fabric thereon together being slightly thicker than the width of the loop 9 between its sides 10 and 12 to frictionally engage the same and firmly hold the fastener in place on the panel and the panel against the frame 2. The length of the lips 10 of the several fasteners, permits however of limited adjustment of the panel upon the frame, and obviates the necessity for extreme accuracy in locating these holes 11 relative to the bores 7 in the frame.

The side 12 of the loop 9 of each fastener, opposite the lip 10, is preferably formed flat and straight to lie flat against the edge portion of the fabric which is turned inwardly and cemented to the face of the board, and this side 12 of said loop is extended and bent substantially at right angles to form a spring hook 13, the end of the spring strip being bent laterally at an angle to said

- straight portion to form an open hook 14 of a width normally somewhat greater than the diameter of the bore 7 into which it is forced, said hook yielding as it is forced in, bringing the sharp angles 15 at the end of the hook, into engagement with the wall of the bore, so that when force is applied tending to withdraw this hook from said bore, these sharp angular corners will dig into the wood and prevent such withdrawal. 5
- 10 In applying the panel 1, said panel is first made up complete with the fabric covering cemented to the board 3, the board being provided with the desired number of holes 11 adjacent its edges, the lips 10 of the fasteners 8 are then slipped into these openings to attach said fasteners to the panel which is then ready to be applied to the frame 2. The fasteners 8 are thus held approximately in position to enter their hooks 13 into the holes or bores 7 in the frame, and the panel may then be firmly attached to the framing by simply pressing these hooks into said bores, they being pressed in until the panel is firmly against the framing or other support, where it will be firmly held by the engagement of the sharp angles 15 of the hooks with the sides of the bores, thus preventing said hooks from being pulled out. 15
- 15 The securing of each panel to its support is thus facilitated and without the use of tools, and the fasteners are covered and completely concealed by the panel. The work of securing these panels in place is thus expedited, and the form of the fasteners and the manner in which they are attached to the panel, permits of a limited adjustment of the panel and also of each fastener, so that extreme accuracy in placing the bores 7 in the framing, is not necessary, nor is great accuracy necessary in forming the panel with the holes 11 therein relative to the bores in the frame or other support or body to which the panels are to be attached. Further, the form of the loops 9 of the fasteners is such that these loops embrace the edge portion of the turned over edge of the fabric and assist in holding the fabric firmly to the board. 20
- 20 Obviously changes may be made in the construction and arrangement of parts, within the scope of the appended claims, and such changes are contemplated.
- Having thus fully described my invention what I claim is:
- 50 1. In a structure of the character described, the combination of a supporting structure having bores of extended length extending inwardly from a face thereof, a finishing panel comprising a fabric covered board with the edge portion of said fabric folded over the edges of said board and extended inwardly from and secured to said edge portions of said board, said board being formed with openings adjacent the edges of said folded over portions of said fabric, and fasteners each formed with a loop having a long lip to be engaged within one of said openings in said board and lie between the face of said boards and fabric and a side opposed to said lip to extend over the adjacent turned over edge portion of said fabric and hold said fabric edge portion to the face of said board, said fasteners each also including a spring hook extending at an angle to said opposed sides of said loop, said hook being of open U-form with the free end thereof adapted to yield and engage the wall of a bore in said support when said hook is pressed therein. 80
- 10 In a structure of the character described, the combination of a finishing panel comprising a fabric covered board formed with a series of openings adjacent to its edges, a supporting frame formed with a series of bores extending inwardly at right angles to the face of said frame to which said panel is to be attached, and a series of fasteners each formed with an end portion to be adjustably engaged within one of said openings in said board and each also formed with a spring hook extending laterally from said end portion with the open end of said hook toward said portion and adapted to be forced endwise into one of said bores to be compressed within said bore and cause the angular corners of the free end of said hook to dig into the wall of said bore wherever positioned within said bore by the forcing of said hook into said bore. 90
- 15 In a structure of the character described, the combination of a finishing member, a supporting member formed with bores of extended length extending inwardly from the surface thereof to which said finishing member is to be applied, and a plurality of fasteners adapted to be attached to said finishing member and each formed with a portion to extend laterally from the inner face of said finishing member to engage within one of said bores, said portion being bent to form a spring arm with its free end extending toward said face, said arm being adapted to engage at its free end, the wall of the bore and secure said finishing member to said supporting member in the position to which it is adjusted when said fasteners are forced into said bores. 105
